DRAFT ATTACHMENT FOR RAILWAY CARS

George T. Johnson, Columbus, Ohio, assignor to
The Buckeye Steel Castings Company, Columbus, Ohio

Application March 3, 1938, Serial No. 193,783

15 Claims. (Cl. 105—420)

This invention relates to improvements in draft attachments for railway cars and the like.

The primary purpose of the invention is to provide a draft attachment structure having a considerable saving in weight over the conventional riveted constructions, either in Grade "B" steel or high tensile steel.

Another object is to furnish a draft attachment which eliminates plates heretofore employed, and thereby not only reduces weight, but economizes on the time and cost of welding.

A still further object is to supply a draft attachment including a bolster center filler designed to facilitate welding.

With the foregoing objects outlined and with other objects in view which will appear as the description proceeds, the invention consists in the novel features herein after described in detail, illustrated in the accompanying drawings, and more particularly pointed out in the appended claims.

In the drawings:

Fig. 1 is a top plan view of one form of my draft attachment, partially in horizontal section, the section being taken on the line 1—1 of Fig. 2.

Fig. 2 is a longitudinal vertical sectional view taken along the center line 2—2 of Fig. 1.

Fig. 3 is an end elevation, partly in vertical transverse section, the section being taken on the line 3—3 of Fig. 2.

Figs. 4, 5 and 6 are views similar to Figs. 1 to 3 inclusive, but illustrating a modification.

Fig. 7 is a top plan view partly in transverse horizontal section of another modification of the bolster center filler and rear draft lug casting; the section being taken on the line 7—7 of Fig. 8.

Fig. 8 is a longitudinal vertical sectional view of such casting taken on the line 8—8 of Fig. 7.

Fig. 9 is a front elevation of the casting partly in transverse vertical section; the section being taken on the line 9—9 of Fig. 8.

Referring to the embodiment of the invention illustrated in Figs. 1 to 3 inclusive, 7 designates the center draft sills which include vertical walls 8 having inwardly extending top flanges 9 and outwardly extending bottom flanges 10; the top flanges of the two sills being secured together by suitable means such as welded joints 11.

My improvements are illustrated in connection with an A. A. R. alternate standard swivel shank coupler 12 and swivel yoke assembly 13, and includes lightweight draft castings which are attached to the draft sills by welding or the equivalent thereof.

The bolster center filler and rear draft lug casting 14, in accordance with the present invention, does not have conventional parallel side walls, but substitutions for these walls are formed by the vertical walls of the center sills.

As is customary, the transversely disposed vertical fronts of the rear draft lugs 15 are arranged in spaced relation at the front of the casting 14, and they are, in the present instance, welded to the draft sills at 16. These lugs are reinforced by upper and lower long ribs 17 and 18 arranged symmetrically about the longitudinal center of the casting and merging at their rear ends at the rear end of the casting, as indicated at 19. 15 These ribs form braces against the top of the center sill, which adequately take care of the eccentricity of buffing stresses with reference to the neutral axis of the draft sills.

The ribs 17 are welded to the flanges 9 at 20, 20 and their outer side edges are welded to the walls 8 at 21. The outer side edges of the ribs 18 are also welded to the walls 8 at 22.

The ribs forming each brace are reinforced by short transverse vertical ribs 25 which have their outer side edges welded to the walls 8 as indicated at 26.

At the rear end portion of the casting, a transverse vertical wall 27 extends entirely across the casting from one wall 8 to the other, and it is 30 welded to the flanges 9, as indicated at 28, and to the walls 8 as indicated at 29.

Other transversely extending vertical walls 30, 31, of less height than the casting, extend in spaced relation entirely across the casting from 35 one wall 8 to the other, and the walls 30 and 31 have their side edges secured to the walls 8 by welded joints indicated at 32.

The vertically arranged king pin sleeve 33 is positioned between the walls 30 and 31, and is integrally connected with said walls by centrally disposed vertical ribs 34. Other transversely disposed vertical ribs 35 project from opposite sides of the sleeve and have their ends welded to the walls 8 as shown at 36.

45 It will be noted that the upper ends of the walls 30, 31 merge into the long ribs 18, as indicated at 37 and 38.

Short substantially horizontal ribs 39, 40, form part of the braces for the rear draft lugs, and extend from such lugs rearwardly to the wall 30. Their side edges are welded to the walls 8 as indicated at 41.

A transversely extending front wall 41x extends across the unit and merges at its upper 50 end into the long ribs 18.

From the foregoing it will be appreciated that I have provided a strong lightweight bolster center filler and rear draft lug casting which, due to its skeleton form, can be readily attached to the draft sills by welded joints.

The front lug castings 42, in accordance with the present invention, are provided with substantially U-shaped flanges 43 which project laterally through key slots 44 in the walls 8, and are welded in position as indicated at 45 and 46. Each of these castings has other portions secured to the draft sills by welded joints indicated at 47.

In the structure illustrated in Figs. 1 to 3 inclusive, the draft sills are notched at their ends as indicated at 48 to accommodate the coupler carrier 49, and the striker casting 50. The latter is designed to extend inside the draft sills, and is arranged so that a minimum of shearing or notching is required. It will be noted that the top flanges 9 of the center sills extend outwardly to the front flange 51 of the striker, as indicated at 52 so that these portions of the sills overlie a rearwardly extending top rib 53 of the striker. Welded joints 54 are employed in securing the striker in position.

To fabricate the arrangement described, the front draft lug castings 42 are first positioned with reference to the ends of the sills 7, and welded into position. The two sides of the center sill are then intermittently welded along the top center line as indicated at 11. Then the casting 14 is positioned with reference to the front draft lugs and welded as illustrated. Afterwards, the striker 50 is applied and welded.

The arrangement and construction shown in Figs. 4 to 6 inclusive is similar to that illustrated in connection with Figs. 1 to 3, with the following principal differences. The bolster center filler casting 14a is made in two parts 14b and 14c which meet along the vertical line A, B, C, D, E, F. The two sections can be welded along such line in the assembling of the structure. The advantage of having this casting made in two pieces or sections is that they can be positioned with reference to the front draft lug castings 42a and welded into position before the two sills 7a are welded together, and therefore, more room is available for welding the sections of the bolster center filler to the sills.

In this modification, the front draft lugs are similar to those shown in Figs. 1 to 3 inclusive, and are secured to the sills in the same general manner.

In the arrangement shown in Figs. 4 to 6 inclusive, the striker 50a is of substantially L-shape in section. Therefore, the draft sills do not have to be notched, as the top flange 53a is horizontally disposed, and is positioned below the top flanges 9a of the sills. Its edge is welded to the flanges 9a as indicated at 54a. The side flanges 53b of the striker are arranged in parallel vertical planes, and they fit within the walls 8a of the sills. These flanges are welded in place as shown at 53d.

In this modified construction, the sills do not have to be notched to fit the striker, and the only punching operation in the sills will be at the key slots 44a.

In assembling the arrangement shown in Figs. 4 to 6 inclusive, one front draft lug, and one section of the bolster center filler are welded to each half of the center sill. The two halves of the latter are then positioned a suitable distance apart, the lugs aligned and the sills welded 75

along the top center as indicated at 11a. The bolster sections are then welded along the line A, B, C, D, E, F, and thus the whole structure is welded into one unit. Afterwards, the striker 50a is positioned and welded.

In both forms of the invention, I prefer to notch the side edges of the casting 14, 14a as indicated at 60, not only to reduce weight, but as the notches are located between the welds on the edges of the ribs, they serve to locate the welds and impart uniformity to the method of applying the castings to the center sill. I also prefer to use welded joints at the lower ends of the sides of the castings as indicated at 61.

In this form of the invention it will be observed that the front ends of the front draft lug castings are in vertical planes as shown at 72. In other words, the front ends are square so as to abut against the rear edges of the sides of the striker 50a. This construction relieves the welds 62 at these points of strain due to forces acting on the draft lugs at 63. It will be noted in this construction that the flanges 64 are of elliptical form and extend completely around the key slots in order to properly position the front draft lugs.

In the embodiment of the invention illustrated in Figs. 7, 8 and 9, the combined bolster center filler and rear draft lug casting is, of course, to be arranged in the center sills in the same manner as illustrated in Figs. 1 to 6 inclusive. However, in this construction, the middle ribs 18 and 38 of Fig. 2 have been replaced by single ribs 65, each of which has at its inner edge portion, an up-turned flange 66, and a down-turned flange 67. These ribs are preferably on the center line of draft. Also in this form of the invention the front vertical ribs 68 have been thickened somewhat and ribs 69 added so as to more uniformly distribute the draft forces. In addition, the vertical ribs have been filleted, as indicated at 70 (Fig. 9), to distribute the vertical forces.

The top, bottom, and two sides of the casting are now generally machined. However, in my invention, in order to eliminate machining, the two sides of the casting are provided with grinding pads 71. These pads are of such size and so located that the surfaces may be ground to gauge and still have sufficient surface to properly space the sills, and to permit welding of the side edges of the casting to the sills.

Many modifications of the invention will be apparent to those skilled in the art without departing therefrom or from the scope of the claims, and since the foregoing disclosure has been given by way of example, for clearness and understanding, no unnecessary limitations should be understood and the appended claims should be construed as broadly as the state of the art permits.

What I claim and desire to secure by Letters Patent is:

1. In a draft structure for railway cars or the like, center sills having spaced walls, and a combined bolster center filler and rear draft lug casting arranged in the sills and having edge portions terminating at the inner surface of the center sills and united with the sills by welding.

2. In a draft structure for railway cars or the like, center sills having spaced walls, and a combined bolster center filler and rear draft lug casting arranged in the sills and having edge portions terminating at the inner surface of the center sills and united with the sills by welded

joints, the front walls of the rear draft lugs being reinforced by upper and lower longitudinally extending transversely disposed ribs which have their outer edges terminating at the inner surfaces of the walls of the sills and secured to said walls by welded joints, the rear end of each lower rib merging into the rear end of a corresponding upper rib.

3. In a draft structure for railway cars or the like, center sills having spaced walls, and a combined bolster center filler and rear draft lug casting arranged in the sills and having edge portions terminating at the inner surface of the center sills and united with the sills by welded joints, the front walls of the rear draft lugs being reinforced by upper and lower longitudinally extending transversely disposed ribs which have their outer edges terminating at the inner surfaces of the walls of the sills and secured to said walls by welded joints, the rear end of each lower rib merging into the rear of a corresponding upper rib, and welded joints securing the inner edges of the upper ribs to the tops of the sills.

4. In a draft structure for railway cars or the like, center sills having spaced walls, and a combined bolster center filler and rear draft lug casting arranged in the sills and having edge portions terminating at the inner surface of the center sills and united with the sills by welded joints, the front walls of the rear draft lugs being reinforced by upper and lower longitudinally extending transversely disposed ribs which have their outer edges terminating at the inner surfaces of the walls of the sills and secured to said walls by welded joints, spaced upstanding walls extending across the casting below the lower ribs and having their side edges secured to the inner surfaces of the walls of the sills by welded joints, a king pin sleeve arranged between said upstanding walls, ribs rigidly uniting the sleeve to the upstanding walls, and transversely disposed ribs extending in opposite directions from the sleeve terminating at the inner surfaces of the walls of the sills and having their side edges secured to the walls of the sills by welded joints.

5. In a draft structure for railway cars or the like, center sills having spaced walls, and a combined bolster center filler and rear draft lug unit arranged in the sills and having edge portions united with the sills by welded joints, the front walls of the rear draft lugs being reinforced by upper and lower longitudinally extending transversely disposed ribs which have their outer edges terminating at the inner surfaces of the walls of the sills and secured to said walls by welded joints, said unit being formed of a plurality of substantially symmetrical cast metal sections positioned at opposite sides of the longitudinal center line of the draft sills.

6. In a draft structure for railway cars and the like, center sills having spaced parallel substantially vertical walls, a combined bolster center filler and rear draft lug unit positioned between said side walls, said unit having a multiplicity of opposed side edge portions abutting against the inner surfaces of said walls, and welded joints rigidly uniting said edge portions with the inner surfaces of said side walls.

7. In a draft structure for railway cars and the like, center sills having spaced parallel substantially vertical walls, a combined bolster center filler and rear draft lug cast unit positioned between said side walls, said unit having side ribs extending longitudinally of the casting and

provided at their inner edge portion with reinforcing flanges, and ribs being welded to the inner surfaces of said sills.

8. In a draft structure for railway cars and the like, center sills having spaced parallel substantially vertical walls, a cast metal combined bolster center filler and rear draft lug unit positioned between said walls, said unit having a multiplicity of opposite side edge portions formed by substantially vertical transverse ribs and substantially horizontally disposed longitudinal ribs, the outer edge portions of said ribs terminating at the inner surface of said walls and being secured to said inner surfaces by welded joints, the inner edge portions of certain of the vertical ribs being filleted and merging into certain of the horizontal ribs.

9. In a draft structure for railway cars or the like, center sills having spaced parallel substantially vertical walls, a cast metal combined bolster center filler and rear draft lug unit positioned between said walls, said unit having a multiplicity of opposed side edge portions and rear draft lugs, welded joints connecting said side edge portions and the outer edges of said lugs to the inner surfaces of said walls, said lugs being vertically disposed at opposed sides of one end of the unit, the unit having longitudinally extending substantially horizontal ribs forming certain of said side edges, and re-inforcing ribs joining said lugs to the upper ones of said longitudinal ribs.

10. In a railway car underframe center sill reinforcing means in the form of skeletal castings, each of said castings comprising a box-like central portion adapted to be welded around its inner perimeter with the abutting casting, an end portion of gradually diminishing depth designed to afford a tapering off section modulus when welded to said center sill, and an opposite end portion comprising a plurality of substantially horizontal ribs adapted to offer maximum resistance to end thrusts when welded to said sill.

11. In a railway car an integrally formed center sill reinforcing skeletal casting comprising a central box-like portion with a center post and cored out walls, and vertically arranged end portions adapted to be welded to a structural steel member forming the center sill of the car, one of said end portions having a depth diminishing gradually from said central portion outwardly, thereby affording a gradually diminishing section modulus when said end portion has been welded to said structural member.

12. In a railway car an integrally formed center sill reinforcing skeletal casting comprising a central box-like portion with a center post and cored out walls, and vertically arranged end portions adapted to be welded to a structural steel member forming the center sill of the car, one of said end portions having a depth diminishing gradually from said central portion outwardly, thereby affording a gradually diminishing section modulus when said end portion has been welded to said structural member, the other of said end portions comprising a plurality of parallel ribs adapted to offer maximum resistance to longitudinal thrusts when welded to said structural member.

13. In a railway car an integrally formed center sill reinforcing skeletal casting comprising a central box-like portion with a center post and cored out walls, and vertically arranged end portions adapted to be welded to a structural steel member forming the center sill of the car, one

of said end portions comprising a plurality of parallel ribs adapted to offer maximum resistance to end thrusts when welded to said structural member, and the other of said end portions comprising a tapering structure adapted to be united to said steel member by a welding operation, thus affording a gradually diminishing section modulus for said united members.

14. In a railway car underframe center sill reinforcing means in the form of skeletal castings, each of said castings comprising a box-like central portion adapted to be welded around its inner perimeter with the abutting casting, and an end portion of gradually diminishing depth designed to afford a tapering off section modulus when welded to said center sill.

15. In a railway car, a center sill structure

comprising symmetrical rolled members adapted to be welded along abutting edges to form a center sill of inverted U section, and reinforcing means in the form of skeletal castings each comprising a central box-like portion and vertically arranged end portions adapted to be welded to the associated rolled member respectively, one of said end portions having a tapering formation adapted to afford a gradually diminishing section modulus when welded to the associated rolled member and the other of said end portions having a plurality of substantially parallel spaced ribs with openings therebetween affording clearance for welding and adapted to offer maximum resistance to end thrusts when welded to said associated rolled member.

GEORGE T. JOHNSON.
